UNITED STATES PATENT OFFICE.

CURTIS WHITE, OF INDIANAPOLIS, INDIANA.

PRINTING-PRESS.

1,150,470.

Specification of Letters Patent.

Patented Aug. 17, 1915.

Application filed May 1, 1914. Serial No. 835,583.

To all whom it may concern:

Be it known that I, CURTIS WHITE, a citizen of the United States, residing at Indianapolis, in the county of Marion and State of Indiana, have invented a new and useful Printing-Press, of which the following is a specification.

It is the object of my invention to provide a perfecting printing press which can be installed in any number of units; in which the number of units can be increased or decreased as desired or needed; in which the parts are so arranged that the number of men required to operate the press is reduced; in which every part of the press is rendered more easily accessible; by which less floor space is required; in which the units of the press can be more easily associated in various ways; in which the various cylinders and other parts are within reach from the floor or deck and can be set without climbing; in which the stereotype plates can be put on and taken off without lifting out the rollers; in which the tympans on the impression cylinders can be changed from the floor ordinarily without necessitating breaking of the sheets; in which the rolls can be changed without stopping the press; by which the number of angle bars required to be used is reduced to a minimum; and in which any combination of colors can be printed and easy changes can be made from black to color combinations and vice versa.

In carrying out my invention, I arrange the two parts or sub-units of each double press or unit substantially one above the other, and mount the rolls of paper below this double press or unit so that the paper is fed upward from the rolls to the lower part of the unit and then to the upper part of the unit for simple black printing on the two sides of the paper. By reason of the vertical arrangement of the two parts of each unit, this does not cause the inclosing of any of the stereotype or impression cylinders in loops of the sheet being printed, so that stereotype plates can be removed and the tympans on the impression cylinders can be replaced without breaking the sheet and without necessitating the lifting of any of the rollers from their place in the press. By reason of this same arrangement, color combinations can be obtained by running the paper from the rolls below the units through the lower part of one of the units and then horizontally from one unit

to the next until the desired combination of colors is obtained. Moreover, because of the vertical arrangement of the two parts of each unit, the units require less floor space. Furthermore, since the paper comes up vertically from the rolls the changing from one roll to another when the paper on the first is used up can be more easily accomplished, and can be done even without stopping the press.

The accompanying drawing illustrates my invention.

Figure 1 is a diagrammatic view showing the general arrangement of the press, the framework being omitted for the sake of clearness; Fig. 2 is a transverse sectional view through the press shown in Fig. 1, the press proper being in elevation; and Fig. 3 is a partial sectional view on the line 3—3 of Fig. 2, showing some details which cannot be brought out in Fig. 1 on account of the small scale of the latter.

The press which I have illustrated in the drawing consists of six units, A, B, C, D, E, and F, each of which units comprises an upper part or sub-unit U and a lower part or sub-unit L, the upper part being substantially over the lower part. There may be any desired number of driving motors, each motor driving one or more units; for simplicity the motors are not shown. Each of these sub-units is for printing on one side of the sheet of paper being printed, and comprises an ink fountain 10 and various ink distributing rollers 11 which carry the ink from the fountain to a stereotype or plate 12 and spread it evenly thereon, and a tympan or impression cylinder 13 between which and the plate cylinder the sheet of paper passes and is printed as it passes. Different ink fountains may be used for black and color printing, if desired, to avoid the necessity of cleaning the fountains when a change in color is made. Various pipe 100 and compensating rollers 14 and angle bars 15 are provided, for guiding the sheet of paper in the desired path, the location of these being variable to a considerable extent. The arrangements of the various rollers and cylinders in the upper and lower parts of each unit are substantially the reverse, the impression cylinders being above and slightly to the left (as seen in Fig. 1) of the stereotype cylinders in the lower part 110 and below and slightly to the right of such roller in the upper part. A cross gangway

16 is provided between each unit and its neighbor on each side, for permitting access to the parts.

The various rollers and other parts of each unit are mounted in a frame 20, the frames of the different units ordinarily being interconnected. The frames 20 rest on cross bars 21 of a floor frame 22 supported on the walls 23 of a subway 24 which extends lengthwise of the press under the several units thereof, as shown in Fig. 1, and is conveniently provided at one end with an elevator 25 for lowering the rolls of paper 26 from the main floor level 27 to the level 15 of the floor 28 of the subway 24. A truck 30 is shown in Fig. 1 in position on the elevator 25. Extending downward into the subway from the floor frame 21 are hangers 31 for supporting a number of the paper rolls 26 just below such floor frame, provision 20 preferably being made for two rolls under each unit, as shown in Fig. 1. There are two hangers 31 for each end of each roll, these two hangers supporting a cross bar 32 which forms a bearing for one end of the shaft 33 of the roll supported by such hangers, said cross bar 32 conveniently being pivoted to one of the hangers 31 and co-operating with a notch 34 in a horizontal 25 flange on the other of the same pair of hangers, as is clear from Fig. 3. In order to lift the roll of paper from the truck 30 to the cross bars 32, said cross bars are dropped, as shown for the roll being lifted in Fig. 3, 30 and hooks 35 carried by lifting chains 36 are placed on the ends of the shaft 33 of the roll 26 to be lifted, the upper ends of the chains 36 being connected to a cross shaft 37 operable in some convenient manner for lifting the roll, there being as many of these 35 cross shafts as there are roll positions, twelve in the press illustrated. Conveniently, these cross shafts 37 are connected by level gearing 38 and clutches 39 to one or 40 more shafts 40 extending along the subway 24, such shaft or shafts 40 being driven through suitable reducing gearing from a motor 41. By this means any of the shafts 37 can be driven from the motor 41 to lift a 45 fresh roll of paper to any roll position.

In order to put tension on the paper as it is being printed, the shaft 33 of each roll is preferably provided with a friction pulley 42, with which co-operate brake shoes 43 on 50 levers 44, said levers being movable toward and from each other to vary the pressure of the brake shoes on the friction pulley, as by means of a right and left hand screw 45 having an operating handle or wheel 46 above the main floor level 27. The lower of each 55 pair of levers 44 may be disconnected and allowed to drop, as illustrated in the one above the car 30 in Fig. 3, to facilitate putting the roll 26 in place or removing the 60 empty shaft 33. It is also sometimes neces-

sary to shift the paper rolls 26 endwise, to make the paper from them engage the cylinders so as to make the proper side margins. This may be done by mounting the levers 44 on a slide 47, which is connected by a rack 70 and pinion 48 to an operating shaft 49 having its operating handle or wheel 50 also above the floor level 27. By turning the handle 50 the slide 47 may be moved parallel to the axis of the roll, carrying the roll 75 with it by reason of the groove provided in the friction pulley 42.

In operation, the paper may be supplied from either of the two associated supply rolls 26 to the lower part L of any press 80 unit. Suppose it is supplied from the roll marked 26' over suitable ones of the pipe rollers 14 so that it passes from the left between the plate cylinder 12 and the impression cylinder 13 of the lower part L of 85 the unit B, being printed in black, say, on the side toward the cylinder 12, and that the paper then passes on freely between the two impression cylinders 13 of the lower and upper parts of the unit B to the left hand 90 side of the impression cylinder 13 of the upper part U and thence from the left between such upper impression cylinder 13 and its co-operating plate cylinder 12 to receive the printing on the other side of the paper, say 95 also in black, passing thence over the pipe rollers 14, and angle bars 15 if necessary, to one of the folders 50, of which there may be any desired number, suitably located as desired, one being shown at each end of the 100 press. It will be noted that the plate cylinder 12 of the lower part L and the impression cylinder 13 of the upper part U of the unit B are accessible from the cross gangway 105 16 between the rollers B and C, and that the other cylinders 12 and 13 of such unit are accessible from the cross gangway 16 between the units A and B, without necessitating any breaking of the sheet being printed, so that stereotype plates may be removed or replaced and make-ready may be placed on the impression rollers when hard or semi-hard packing is used, as desired and with comparative ease. In case the paper 110 on the roll 26' is approaching its end, the beginning of the paper on the adjacent roll 26' for the same unit is run up over the pipe rollers 14 as illustrated in Fig. 1, and paste is applied across the front edge of this new 115 roll. Then, just before the end of the paper on the first roll is reached, the pasted end of the new roller is thrust quickly over on to the passing paper from the old roll, and the paper from the first roll broken behind the pasted joint. This can be done without 120 stopping the press, although it is found best to slow down the press in order to avoid too great a jar from starting the new roll, and by proper judgment there is but little waste 125 paper left on the old roll, the pasted end 130

of the new roll being applied very close to the end of the paper from the inside of the old roll.

With the double sextuple press shown, simple black printing may be done in all the units at once in every desired combination, without leaving any units idle. Thus the press may be used as two sextuple presses; as an octuple press and a quadruple press; as three quadruple presses, in which latter case the two sides of each of four units work on separate papers and corresponding sides of each of the four units coöperate for a single paper, the two sides of these four units coöperating with different holders.

When colors are to be printed, various combinations of the different units can be made. One of these is illustrated in Fig. 1, the paper from the roll 26''' passing up over the proper pipe rollers between the stereotype roller and the impression roller of the lower part L of the unit C, exactly as in the case of the unit B, and passing thence, over compensating rollers is necessary, to the lower part L of the unit D through which it passes in the same manner, and thence to the lower parts L of the units E and F in succession, through which it passes in the same manner; thence it passes backward between the upper and lower parts of the several units around the impression roller 13 of the upper part U of the unit C, passing from left to right between the rolls 12 and 13, and from thence to the upper parts of the units D, E, and F in succession, through which it passes in the same manner; thence it may pass over the proper pipe rollers 14, and angle bars 15 if necessary, to the same folder and counter 50 to which the printed paper from the unit B is supplied, the paper from the two rolls being cut and folded together. In this color combination scheme, the unit C may supply yellow ink, the unit D red ink, the unit E blue ink, and unit F black ink, which is the usual combination used in up-to-date newspapers for their colored supplements.

Many other color combinations can be used, by very simple and obvious arrangements of the units and sub-units. For instance, by using two units together as a quadruple press to print a sheet with black on one side and black and two colors on the other, the sheet may be supplied to the lower sub-unit of one of the units, say B, to print black on one side of the sheet, and passed thence to the lower sub-unit of the second unit, say A, but with this sub-unit operating in the reverse direction from normal, and passing thence through the two upper sub-units of the two units A and B in succession, as illustrated in dotted lines in Fig. 1. In this arrangement, the margin bars 65 on different parts of the plate cylinders

should be spaced by 90° instead of 45° , so that the headings on the two sides of the roller may register with those of the other sub-units. This also necessitates that the sub-unit operating in the reverse direction (sub-unit L of unit A) have other ink distributing rollers for the most desirable distribution of ink during this backward rotation of the parts.

I claim as my invention:

1. A printing press comprising a series of perfecting units arranged in a line, the several units each having plate and impression cylinders transverse to such line, a subway extending longitudinally beneath said series of units, means for supporting a roll of paper crosswise in said subway below each of said units, a cross shaft extending across said subway for each of said roll-supporting means, a motor-driven longitudinal shaft extending along said subway and connectible to any of said cross shafts, and lifting means associated with each of said cross shafts for lifting a roll of paper to the position in which it is to be supported in said subway.

2. A printing press comprising a series of perfecting units arranged in a line, the several units each having plate and impression cylinders transverse to such line, a subway extending longitudinally beneath said series of units, means for supporting a roll of paper crosswise in said subway below each of said units, a cross shaft extending across said subway for each of said roll-supporting means, means for operating any desired one of said cross shafts, and lifting means associated with each of said cross shafts for lifting a roll of paper to the position in which it is to be supported in said subway.

3. A printing press comprising a plurality of press units, each of which extends transversely of the whole press, a subway extending longitudinally beneath the press and under said units, means for supporting one or more rolls of paper in said subway below each unit and sufficiently above the subway floor to allow other rolls to pass beneath such supported rolls.

4. A printing press comprising a plurality of units, a subway extending longitudinally beneath said units, means for supporting one or more rolls of paper in said subway below each of said units, means associated with each of said supporting means for raising and lowering a roll of paper from the subway floor to such supporting means, a source of power, and means for connecting such source of power to any of such raising and lowering means.

5. The combination of a perfecting printing press and means located beneath said press for supporting a plurality of rolls of paper close to each other, and separate pipe

4
rollers close to each other beneath said press for receiving paper from the different rolls so that paper fed upward from any roll may be supplied to the press and the paper from one roll may be gotten in readiness for starting prior to the discontinuance of supply from another roll.

6. In combination, a printing press, a subway extending beneath said printing press, means for supporting a plurality of rolls of paper in the upper part of said subway with their axes transverse thereto, a cross shaft extending across said subway for each of said roll-supporting means, a motor-driven longitudinal shaft extending along said subway and having a separable driving connection with each of said cross

shafts, and lifting means associated with each of said cross shafts for lifting the rolls of paper to the position in which they are 20 to be supported in said subway, said rolls when supported in the upper part of said subway being sufficiently above the bottom of said subway to allow the passage of other rolls beneath them.

25

In witness whereof, I, have hereunto set my hand at Indianapolis, Indiana, this twenty-ninth day of April, A. D. one thousand nine hundred and fourteen.

CURTIS WHITE.
